UNITED STATES PATENT OFFICE.

LEO SCHILDKNECHT, OF ST. LOUIS, MISSOURI, ASSIGNOR TO LANDIS MACHINE COMPANY, OF ST. LOUIS, MISSOURI, A CORPORATION OF MISSOURI.

SHARPENING TOOL.

Application filed March 23, 1926. Serial No. 96,711.

My invention relates to sharpening tools and is particularly adapted for sharpening an awl or a similar tool which has a point, the faces of which are required to be fairly exact in order to secure the best results from its use. As an example of such a tool, I refer to the curved awl which is in general use in curved needle stitchers such as are used for shoe repairing. In such machines, the awl is used to perforate the leather and the passage of the awl through the leather is followed by the passage of the needle. If the shape of the awl point is not exact, the point of the needle will not have an accurate opening provided for it and the stitching will be uneven and otherwise defective. Sometimes the needle will be broken. In fact, the awl has been described as being the "soul" of the stitcher so far as satisfactory work is concerned. It has long been customary to file such awls by hand but as many machine operators have no other mechanical training, such hand-filing is often highly unsatisfactory. In an effort to provide a more exact means for pointing such awls, it has been proposed heretofore to provide a holder for the awl and guides associated therewith for controlling the movement of the files or other sharpening instruments which are used by the operator. At best such devices depend upon the correct positioning of the file in the guide by the operator. After some use, the guides are worn away by the files and the device is no longer accurate.

The objects of my invention are to provide a simple economical awl sharpening device in which the pointing of the awl may be easily and exactly secured by a person who has no mechanical skill.

In the accompanying drawings which illustrate a selected embodiment of my invention,

Figure 1 is a top view of my device.

Figure 2 is a side elevation of the same sectioned in part to more clearly illustrate its construction.

Figure 3 is an end elevation of my device looking toward the righthand end of the same as shown in Figure 2.

Figure 4 is a horizontal section taken on line 4-4 of Figure 2.

My device comprises a base 1 which includes a depending bracket 2 whereby the device may be clamped to a table or shelf T by

means of a clamping screw 3 having a wing nut handle 4. The base 1 also includes an upstanding bracket 5 having spaced grooves 6 and 7 adapted to receive abrasive instruments such as files 8 and 9, respectively. Each file is secured in its respective groove or slot by a clamping screw 10 which is threaded into the adjacent portion of bracket 5. The files are fixedly held at different angles to the vertical with flat faces converging toward each other crosswise but extending lengthwise in parallel with each other.

The device includes a compound slide which is formed by a pair of gibs 11 formed in base 1 and extending transversely of the same, a member 12 slidably mounted on gibs 11 and having a pair of gibs 13 extending transversely of gibs 11, and a block 14 with an enlarged flange 15 slidably mounted in gibs 13.

Block 14 is the tool holding element and is provided with a curved groove for receiving one edge of an awl A which is held in place by a plate 16 attached to the block by a bolt 17 and knurled nut 18.

The point of the awl is really an edge and it is desirable that this edge have a predetermined angle with the adjacent portion of the awl and to produce the desired angle I provide a setting gauge 19 which is shown as being mounted on the upper end of bracket 5 but located outside of file 8.

To use the device the awl is inserted between plate 16 and block 14 and screw 18 tightened sufficiently to yieldingly hold the awl.

The block is moved (see Figure 2) so that the point of the awl is under gauge 19 and the awl is then moved in block 14 and plate 16 until its point contacts with the underside of gauge 19. Screw 18 is then tightened. The block is then moved in the direction of arrow X until the awl passes beyond the ends of files 8 and 9.

The block and slide member 12 is then moved in the direction of arrow Y (see Figure 3) until the point of the awl is opposite the space between files 8 and 9.

The block is then moved along gibs 13 so as to contact the awl with the inner faces of one of the files, such movement transversely of the files as may be necessary to provide contact being attained by movement of slide 12 in gibs 11. After a few reciprocal movements of the block and awl along one of the files, the slide 12 is

moved to contact the awl with the other file and reciprocal movement of the block in slide 12 with the awl against the other file will produce a sharp edged point on the awl 5 point which will be accurate as to the inclination of the point forming surfaces and as to the angle between the point edge and the curve of the awl.

The only skill required in sharpening the 10 awl is that necessary to avoid filing a substantially greater amount on one surface than on the other as the edge of the awl point should be aligned with the longitudinal edges of the awl which is square in 15 cross section.

Irrespective of the movements of slide 12 and block 14 in their respective gibs, the awl cannot be turned pivotally, either horizontally or vertically, so as to vary the relation 20 between the surfaces produced by the files or to vary the inclination of the edge formed by the meeting of these surfaces.

The files may be repeatedly adjusted or 25 reversed in their respective grooves so as to present different portions of their surfaces to the awl, thereby making possible extended provision of a sharp abrasive surface. Such adjustments will not affect the angles at which the files are held.

30 The parts of the device are easily made and assembled and the device as a whole can be attached to any table, bench, shelf, or other object having a projecting ledge, or the device may be operated when held in 35 the hand even if not attached to any rigid supporting object.

It is not essential that the two parts of the compound slide move at right angles to each other, although this is the preferred 40 construction. Obviously similar results would be obtained if the respective pairs of gibs were disposed at forty-five degrees to each other or at other angles to each other.

This and other details of my invention 45 may be modified without departing from the spirit thereof and I contemplate all such modifications as come within the scope of my claims.

I claim:—

50 1. In a sharpening device for an awl or like tool, a base, an upstanding member at one end of said base, file holding means on the upper portion of said member, and tool holding elements slidable on said base longitudinally and transversely of said means, said member and elements serving to hold a file and awl carried thereby at a predetermined angle to each other.

55 2. In a device for sharpening an awl or like tool, means for holding an abrasive instrument at a predetermined angle, a tool holder movable in different directions at angles to each other and having predetermined relation to said means, said tool holder being held against pivotal movement

relative to said means, and a gauge on the device for positioning the point of a tool positioned in said holder.

3. In a device for sharpening an awl or like tool, a pair of abrasive instruments with 70 converging surfaces extending lengthwise and parallel with each other, means for holding said instruments as described, a tool holding element, means for guiding said element so that the tool may be moved along 75 the surface of either of said instruments or moved at an angle to said surfaces, said means preventing pivotal movement of said tool relative to said surfaces, and a gauge located approximately at the level of said instruments and adapted to position the point 80 or end of a tool mounted in said element.

4. In a device for sharpening an awl or like tool, a base, a member slidable thereon in one direction, an element slidable on said member in a transverse direction, means on 85 said element for holding an awl, a bracket on said base, a pair of files mounted on said bracket and extending over said base, a gauge at one side of said files and extending 90 over said base whereby the end of the tool may be positioned relative to said base, said files terminating short of the end of the base opposite said bracket to permit the movement of the awl point around the end of 95 said files from beneath said gauge to between said files.

5. In a device for sharpening an awl or like tool, a base, a clamp for attaching said base to a shelf or like projection, parallel 100 gibs on said base, a slide mounted in said gibs, parallel gibs on said slide extending at an angle to said base gibs, a block mounted on said slide, means for holding an awl on the side of said block, an upstanding arm 105 at one end of said base, a pair of inclined slots in said arm, flat files in said slots, screws in said arm for fastening said files to said slots, a gauge on said arm intermediate the top and bottom of said files for 110 positioning the point of an awl held on said block, said files extending over said base and terminating short of the end thereof opposite to said arm to permit the movement of the awl point around the ends of said files. 115

6. In a portable sharpening mechanism for an awl or like tool, a base, an upstanding member on said base, a pair of abrasive instruments fixedly mounted on said member and extending over said base, a compound slide device on said base beneath said instruments, said device including a primary element slidable on the base and a secondary element slidable in a different direction on the primary element, said elements being movable at angles to each other in their respective directions, and means on said secondary element for holding an awl. 120

7. In a portable sharpening mechanism for an awl or like tool, a base, an upstand- 125

ing member on said base, a pair of abrasive instruments fixedly mounted on said member and extending over said base, a compound slide device on said base beneath said instruments, said device including a primary element slidable on the base and a secondary element slidable in a different direction on the primary element, said elements being freely movable at angles to

each other in their respective directions, 10 means on said secondary element for adjustably holding an awl, and an awl gauge on said member extending over said base adjacent to said instruments.

In testimony whereof I hereunto affix my 15 signature this 13th day of March, 1926.

LEO SCHILDKNECHT.
